(57) **CLAIM**

The ornamental design for a rolling brush for a cleaning robot, as shown and described.

DESCRIPTION

1.1 is a front view of a first embodiment of a rolling brush for a cleaning robot, showing the new design;

1.2 is a rear view thereof;

1.3 is a left view thereof;

1.4 is a right view thereof;

1.5 is a top view thereof;

1.6 is an enlarged top view thereof;

1.7 is a bottom view thereof;

1.8 is an enlarged bottom view thereof;

1.9 is a front, top perspective view thereof;

1.10 is a reverse front, bottom perspective view thereof;

1.11 is a top perspective view thereof, featuring callout region **1.12**;

1.12 is an enlarged view of callout region **1.12** of **1.11**;

2.1 is a front view of a second embodiment of a rolling brush for a cleaning robot, showing the new design;

2.2 is a rear view thereof;

2.3 is a left view thereof;

2.4 is a right view thereof;

2.5 is a top view thereof, featuring callout region **2.6**;

(Continued)

2.6 is an enlarged view of callout region **2.6** of Fig. **2.5**;
2.7 is an enlarged top view thereof;
2.8 is a bottom view thereof;
2.9 is an enlarged bottom view thereof;
2.10 is a reverse front, bottom perspective view thereof;
2.11 is a rear, top perspective view thereof;
2.12 is another rear, top perspective view thereof;
2.13 is a top perspective view thereof, featuring callout region **2.14** and callout region **2.15**;
2.14 is an enlarged view of callout region **2.14** of Fig. **2.13**;
and
2.15 is an enlarged view of callout region **2.15** of Fig. **2.13**.
The broken lines in the drawings are used only for illustrating the boundaries of the enlarged callout regions and form no part of the claimed design.
